(57) **CLAIM**

The ornamental design for a display screen or portion thereof with an animated graphical user interface, as shown and described.

DESCRIPTION

FIG. 1 is a front view of a first image of a display screen or portion thereof with an animated graphical user interface; FIG. 2 is a front view of a second image thereof; FIG. 3 is a front view of a third image thereof; FIG. 4 is a front view of a fourth image thereof; FIG. 5 is a front view of a fifth image thereof; FIG. 6 is a front view of a sixth image thereof; FIG. 7 is a front view of a seventh image thereof; FIG. 8 is a front view of an eighth image thereof; FIG. 9 is a front view of a ninth image thereof; FIG. 10 is a front view of a tenth image thereof; FIG. 11 is a front view of an eleventh image thereof; FIG. 12 is a front view of a twelfth image thereof; FIG. 13 is a front view of a thirteenth image thereof; FIG. 14 is a front view of a fourteenth image thereof; FIG. 15 is a front view of a fifteenth image thereof; FIG. 16 is a front view of a sixteenth image thereof; FIG. 17 is a front view of a seventeenth image thereof; FIG. 18 is a front view of an eighteenth image thereof; FIG. 19 is a front view of a nineteenth image thereof; FIG. 20 is a front view of a twentieth image thereof;

(Continued)

FIG. 21 is a front view of a twenty-first image thereof; FIG. 22 is a front view of a twenty-second image thereof; FIG. 23 is a front view of a twenty-third image thereof; FIG. 24 is a front view of a twenty-fourth image thereof; and, FIG. 25 is a front view of a twenty-fifth image thereof. The appearance of the image transitions sequentially between the images shown in FIGS. 1-25. The process or period in which an image transitions to another forms no part of the claimed design. The broken lines showing a display screen or portion thereof in all views forms no part of the claimed design.
